UNITED STATES PATENT OFFICE.

JAMES A. SCOTT, OF WORCESTER, MASSACHUSETTS.

FOLDING BOX AND COVER.

1,156,250.

Specification of Letters Patent.

Patented Oct. 12, 1915.

Application filed July 24, 1913. Serial No. 780,901.

To all whom it may concern:

Be it known that I, JAMES A. SCOTT, a citizen of the United States, residing at Worcester, in the county of Worcester and 5 Commonwealth of Massachusetts, have invented a new and useful Improvement in Folding Boxes and Covers, of which the following is a specification accompanied by drawings, forming a part of the same.

10 The object of my present invention is to provide a box of cardboard or similar material, having the bottom and sides of the box, and the sides and top of the cover permanently attached, but composed of jointed 15 sections conveniently formed by scoring the cardboard on suitable lines to form hinge joints, whereby the bottom and sides may be folded together in a flat or compact form, and the top and sides of the cover may be 20 folded in flat form suitable to be stacked one upon another for convenience in transportation and storage. I accomplish this object by the construction hereinafter described and illustrated in the accompanying drawings, in which—

Figure 1 is a perspective view of a paper box and cover embodying my invention. Fig. 2 is a perspective view of my improved box with the cover removed. Fig. 3 is a plan 30 view of the sheet of cardboard prepared to form the bottom of the box. Fig. 4 is a perspective view of the box with the cover removed, and represented as partially folded. Figs. 5 and 6 represent the box in perspective view at progressive stages of the folding operation. Fig. 7 represents the box in its folded condition. Fig. 8 is a perspective view of the inside of a box cover embodying my invention. Fig. 9 represents the box 40 cover in a folded condition. Figs. 10 and 11 illustrate a modified form of construction.

Similar reference letters and figures refer to similar parts in the different views.

Referring to Fig. 1 of the drawings, 1 45 denotes the body portion of the box and 2 the cover, both in the present instance being rectangular in shape. The box proper consists of a bottom 3 formed from a sheet of cardboard represented in Fig. 3. The bottom 50 3 has a scored line 4 extending diagonally across the bottom and forming a hinge joint dividing the bottom into two triangular sections 5 and 6, the scored line 4 being cut on that side of the sheet which is to 55 form the inside of the bottom. The corners of the bottom are clipped, as represented at

7, and scored lines 8 are cut on the side opposite the side having the scored line 4 inclosing a rectangular space to form the bottom of the box. The margins between the 60 scored lines 8 and the outer edge of the sheet represented in Fig. 3 are turned up on the scored lines 8, forming flanges 9, to which the sides of the box are attached by staples 10, or otherwise permanently united. 65

The sides of the box are preferably formed, as shown in Fig. 2, from two rectangular sheets of cardboard, one forming the sides 11 and 12 of the box, and the other forming the sides 13 and 14, said sides being 70 united to the bottom by the staples 10, and also permanently joined to the opposite or diagonal corners by means of staples 15, or otherwise suitably attached.

The inner side of the box side 11 is scored 75 on the line 16 diagonally across the side and extending from the lower corner 17 of the box to a point 18 at its upper edge. The side 13 of the box is similarly scored on the inside upon a diagonal line 19 extending across 80 the side from the lower corner 20 to a point 21 at the upper edge of the box. The scored line 16 forms a hinge joint extending obliquely across the side 11, dividing the side of the box into two sections 22 and 23, and 85 the scored line 19 forms a similar hinge joint in the side 13, dividing the side 13 into two sections 24 and 25.

In order to collapse the box the sides 11 and 13 are pushed inward, folding on the 90 lines 16 and 19, and at the same time the bottom 3 is pushed upward toward the interior of the box.

At the beginning of the folding operation the box will assume the shape represented in Fig. 4. A continued pressure against the outside of the sides 11 and 12 will still further collapse the box, bringing it into the shapes successively shown in Figs. 5 and 6. From the shape shown in 100 Fig. 6 the sides are pressed together against the bottom, forming a flat parcel, as represented in Fig. 7.

The cover 2 of the box represented in perspective view is constructed from a single 105 rectangular piece of cardboard having its edges scored and turned up to form flanges 26 and 27 which are united at the corners of the cover by staples 28, or otherwise suitably attached. The flanges 26 and 27 when 110 thus united at the corners form sides adapted to telescope over the outside of the box

3, as shown in Fig. 1. The flanges 27 are each scored upon their outer sides on lines 29, extending from the corners of the cover obliquely across the flanges 27, said scored lines 29 forming a hinge joint. In order to collapse the cover the flanges 27 are turned outwardly and the flanges 26 are turned inwardly against the top of the cover and the flanges 27, forming a flat parcel as represented in Fig. 9.

In Figs. 10 and 11 I have shown a slight modification which consists in constructing the bottom of the box in two triangular halves 30 and 31, the section 30 being integral with the side 32 of the box and the section 31 being integral with the side 33 of the box. The section 31 is provided with a flange 34 separated from the section 31 by a scored line 35. In forming the bottom of the box from the two sections 30 and 31 the flange 34 is slipped beneath the section 30 and the two are united by staples 36. When the sections 30 and 31 are united the bottom may be folded on the scored line 35, in the same manner as already described.

My improved folding box possesses many advantages over the method now practised in constructing folding boxes. All the corners of the box may be permanently united at the factory and when collapsed not only become very compact but are also less liable to be injured in shipment, as the different parts of the box when folded could mutually support and protect each other. The collapsed box requires no rebuilding when

required for use, it being sufficient to simply restore it to its original rectangular form. When extended in the form shown in Fig. 2, and a cover applied as shown in Fig. 1, the box is prevented from collapsing by the cover, which must be removed before the box is folded and the accidental removal of the cover is conveniently prevented by a tape 37 attached to the sides and tied across the cover, as represented in Fig. 1.

I claim,

A folding box, having a rectangular bottom, scored along its edges to provide hinged upstanding flanges, said bottom being scored diagonally, walls for said box, consisting of a pair of sides each co-extensive with two adjacent edges of the bottom and joined to the corresponding hinged flanges thereof, each of said sides being scored to correspond to the corner of the bottom, and one end of each side being scored to provide a hinged attaching edge for the adjacent end of the other side, a pair of the opposite walls formed by said sides being scored obliquely from diagonally opposite corners of the bottom to intermediate points along their upper edges, whereby the said opposite walls may be folded upon themselves as they are folded inwardly upon the bottom.

Dated this nineteenth day of July 1913.

JAMES A. SCOTT.
